Specification for Design.

Patented Jan. 28, 1919.

Application filed October 5, 1918. Serial No. 257,068. Term of patent 14 years.

To all whom it may concern:

Be it known that I, DUNCAN A. McCONNELL, a citizen of the United States, and a resident of Montclair, in the county of Essex and State of New Jersey, have invented a new, original, and ornamental Design for Mechanically-Actuated Diaphragm-Horns, of which the following is a specification, reference being had to the accompanying drawings, forming part hereof.

The figures of the drawing show the design of the article.

Figure 1 is a side elevation and Fig. 2 is a rear elevation showing the design of the article.

I claim:

The ornamental design for a mechanically-actuated diaphragm horn, as shown.

DUNCAN A. McCONNELL.
